SWITCH-CONTROLLING SYSTEM.

1,109,657.

Specification of Letters Patent.

Patented Sept. 8, 1914.

Original application filed October 31, 1910, Serial No. 589,958. Divided and this application filed August 11, 1913. Serial No. 784,225.

To all whom it may concern:

Be it known that we, CLARENCE E. BEACH and HERMAN W. DOUGHTY, of Binghamton, in the county of Broome and State of New York, have invented certain new and useful Improvements in Switch-Controlling Systems, of which the following is a specification.

Our invention relates to systems of controlling switches for use at the central offices of normally closed circuit signaling systems, as for example, fire alarm systems in which an automatic repeater is employed in connection with a plurality of signaling circuits, such repeaters being so arranged that when the magnets representing any one signal circuit become deenergized, the repeater acts to break all of the other circuits connected therewith, and therefore especial care must be exercised in connecting individual circuits to or disconnecting them from such a repeater, to avoid tripping the repeater during such operations and thereby sending a false signal over all of the other circuits connected with such repeater. Such repeaters are further so constructed that after having acted to break the circuits connected therewith, they again act after a predetermined period to close their circuit connections, even though the circuit which caused their initial operation is still deenergized. For reasons well understood by those skilled in the art, it has been the practice, prior to our present invention, to provide switches and a gang rod by means of which they could be operated as a unit, so that in the event of its becoming desirable to disconnect any circuit from the repeater while such circuit was closed, all circuits could be simultaneously disconnected from such repeater so that none of the circuits would be broken by the resulting operation of the repeater, and subsequent to the repeater acting to close its circuits, certain circuits could be again connected with the repeater while leaving the desired circuit or circuits disconnected therefrom. When the various circuits are thus disconnected from an automatic repeater, it is sometimes desirable that they should be connected in series with each other, so that breaks in any circuit incident to the transmission of a signal therein would interrupt the flow of current through all circuits;

while under certain other circumstances, it is essential that the circuits be not only disconnected from the repeater, but that they shall not be connected to each other, as for example, when one or more of the circuits are "grounded" or "crossed" with some foreign circuit. To meet both of these conditions, controlling switches have been constructed, having movable members adapted to connect with any one of three sets of contacts, and constructed so that when passing from one set of contacts to another they would connect with the second set of contacts before breaking from the first. Means have also been provided for simultaneously moving a plurality of these switches either to a position where the signaling circuits are connected in series with each other or to a position where they are left independent of each other, being disconnected from the automatic repeater in both positions; and between such two positions, a position has been supplied, providing for the separate connection of such circuits to the automatic repeater. Considerable difficulty has been experienced in the use of such switches, due to the fact that it is frequently necessary to manipulate these switches at a time when the operator must act in great haste or under stress of excitement, and the repeater connection position being intermediate between the two cutout positions, it has been found to require the exercise of an undesirable degree of care to move these switches to the position operatively connecting the circuits with the repeater and stop the switches exactly in such position, it being evident that if any of the switches are moved beyond this position, from either of their extreme positions, such circuits are first connected to the repeater and then disconnected therefrom, thereby causing the transmission of a false signal over all other circuits connected with the repeater. It has likewise been found very difficult to move a plurality of these switches simultaneously, from either of the positions which they occupy while the repeater is disconnected, without either moving some of the switches too far, and thus tripping the repeater and leaving such circuits disconnected, when the position of their switches apparently indicates that they are connected to the repeater, or else failing to move all of the switches far enough.

to properly connect their circuits to the repeater.

An object of this invention is to provide improved switch controlling means whereby all the switches controlling the connections between different circuits on such a repeater or other signaling instrument may be adjusted to be simultaneously moved by means of a suitable actuating member, and so that any desired switch or switches may be detached from such actuating member and either moved independently or adjusted to permit the movement of said actuating member without moving such switches, and further providing means whereby when such actuating means has moved any or all of said switches to an abnormal position where the circuits represented by such switches are disconnected from the repeater, the number of switches responsive to the operation of the actuating means may be either increased or decreased, and thereupon all responsive switches may be quickly moved to the position where their circuits will be operatively connected to the repeater, without danger of over-running such position in the instance of any individual switch, and therefore without danger of either rendering the connection between any circuit and the repeater inoperative or causing a false stroke to be sounded on any of the circuits controlled by the repeater.

A further object of this invention is to provide means whereby the actuating mechanism may be so adjusted as to positively arrest the motion of any switch or switches when moved to the position where they connect their circuits in operative relation to the repeater, thereby permitting such switches to be individually moved quickly and accurately from a position which disconnects their circuits from the repeater to the position which operatively connects them, without danger of over-running such position.

For the fulfilment of the foregoing objects, we provide a switch operating bar having automatic means for locking it when it is moved to its normal position and permitting said bar to be released for movement to one of its abnormal positions, without leaving it free to be moved to its other abnormal position, and such detachable means for connecting switches for a plurality of circuits to the bar, that any or all of said switches may be simultaneously operated by means of said bar; that any switch may at any time be rendered unresponsive to any movement of said bar; and further that when said bar is in its normal position, any individual switch which stands in an abnormal position may be adjusted to be automatically locked to prevent overrunning when it is moved to its normal position.

In order that our invention may be better understood, we show, in the drawings accompanying and forming part of this specification, a form of our controlling system which is suited to be applied to a municipal fire-alarm switchboard to adjust switches such as are shown in the co-pending application Serial No. 589,958 filed October 31, 1910, of which this is a division. Only the mechanical apparatus is herein shown and described as the electrical arrangement and operation of such switches are described in detail and claimed in said co-pending application. It is evident that our invention is equally well adapted for use with other classes of circuits and we therefore do not desire to limit ourselves to the form or arrangement of parts shown in the drawings and hereinafter described, as various changes in form and arrangement, and the insertion or omission of various parts, may be made without departing from the spirit of our invention.

In the drawings forming part of this specification and in which like numerals of reference are used throughout:—Figure 1 is a front elevation of a portion of a switchboard equipped with our controlling switches; Fig. 2 is an enlarged section of a portion of Fig. 1; Fig. 3 is a section on the line A—A of Fig. 1 with the bolt in position to engage the yoke of the gang switch and Fig. 4 is a section of the parts shown in Fig. 3 with the bolt withdrawn.

Referring to Fig. 1, the gang switches 5, 6 and 7, one for each circuit, each comprises the switch arms 8, 9 and 10, which are mounted on the pivots 11, 12 and 13 respectively, and three contact points for each arm, those showing in the figure being 14 and 15 for arm 8 and 21 and 22 for arm 10. These contact points are so spaced and constructed that when one of the switch arms 8, 9 or 10 is moved from one of said contact points with which it engages to another, such arm will not cease to be in contact with one of such contact points until it is in contact with the other. The yokes 23 made of insulating material are provided and connected to the free ends of the said switch arms and the stops 25 are provided for limiting the travel of said switches.

In signaling systems employing a transmitting or repeating signaling instrument, it is usual to provide switches whereby all the circuits can be simultaneously connected to or disconnected from such instrument; and when so disconnected be either in series with each other, or by use of a separate set of switches be left in parallel with and disconnected from each other, and to provide independent switches whereby any circuit can be disconnected from such instrument, while leaving the others connected thereto. By the use of the system of wiring shown in

the divisional application in connection with the mechanism shown herein, all of these results are accomplished with the use of the one set of gang switches.

5 The yokes 23 are provided with notches 43 (see Figs. 1, 3 and 4) adapted to be engaged by the bolts 44, mounted in the sleeves 45 carried by the bar 46. The bar 46 is provided with slots 47 which slots are of such 10 width as to permit the body of the screw 48 to pass through freely, and of such length as to permit the bar 46 to have the necessary longitudinal travel. The posts 49 (see Fig. 2) are mounted in suitable relation to the 15 yokes 23 so that when the bar 46 is attached to said posts by means of the screws 48 the travel of the bolts 44 will be coincident with the travel of the notches 43. The arm 50 is pivoted at 51 and is provided at its free end 20 with the handle 52 and is connected to the bar 46 by the bolt 53. The sleeves 45 are provided with a recess containing the spring 55, one end of which spring rests against the shoulder 45' of the sleeve 45, and the other 25 end of said spring 55 presses against the shoulder 44' formed on the bolt 44 (see Figs. 3 and 4) thus tending to move said bolts into a position where they will engage the notches 43. A slot 54 is provided in one wall of the sleeves 45 and the pins 56 carried by the bolts 44 are arranged to move in the slot 54, thus providing a limit for the travel of said bolts 44 in the direction of the yokes 23. Said slots 54 are of such length that, 30 when the bolts 44 are fully withdrawn from the path of the notches 43, the pins 56 may be fully withdrawn from the slots 54, and thereupon the bolts 44 may be held out of engagement with the notches 43 by turning 35 said bolts 44 so as to bring the pins 56 out of line with the slots 54 (see Fig. 4); the knobs 57 being provided for the purpose of operating the bolts 44.

The spring catches 58 and 58' (see Figs. 45 1 and 2) are provided at their free ends with the operating knobs 59 and 59' respectively; the spring catch 58 being mounted upon the bar 46 in such relation to the head of one of the screws 48 as to tend to engage 50 therewith whenever it is attempted to move the bar 46 from its normal position (where the engagement of the bolts 44 with the notches 43 would cause the yokes 23 to hold the respective switch arms in engagement 55 with their central contact points) to the position where the engagement of said bolts 44 and notches 43 would cause said switch arms to be brought into contact with their corresponding left hand contact points; and 60 the spring catch 58' is so mounted upon the bar 46 as to tend to engage with the head of one of the screws 48 whenever it is attempted to move said bar 46 from its normal position, hereinbefore described, to the position 65 where, by means of the engagement of

the bolts 44 with the notches 43, the various switch arms would be brought into contact with their corresponding right hand contact points. The spring catches 58 and 58' are of such form and material that they 70 are sufficiently flexible to permit their free ends being sprung away from the bar 46 by their knobs 59 and 59', so that the heads of the screws 48 will not obstruct the movement of said catches, and they will thus permit the bar 46 to move longitudinally. 75

When all the parts are in their normal positions, the bar 46 is locked by the engagement of the free ends of the spring catches 58 and 58' with their respective 80 screws 48, the bolts 44 are projecting into the notches 43, and the gang switches 5, 6 and 7 are thereby positively held in the position where their switch arms are resting upon their central contact points (see switch 85 7, Fig. 1). In this position the circuit represented by the switch is connected to the corresponding unit of the repeater. If it is desired to disconnect all the circuits from the repeater and so connect said circuits together that they will form one series circuit, this can be done by disengaging the 90 spring catch 58', by means of the knob 59' from the head of the screw 48 with which it normally engages, and then moving the 95 arm 50 to the right (toward the "series" indication), by means of the handle 52, and thus moving the bar 46 and the switches 5, 6 and 7, which are connected to said bar 46 by means of the bolts 44 until the arms 100 10 of said switches 5, 6 and 7 have been moved to the right until they are brought against their stop-pins 25 (see switch 5 in Fig. 1). If it is desired to disconnect all 105 the circuits from the repeater and leave all 110 of such circuits disconnected from each other, this can be done by disengaging the spring catch 58, by means of the knob 59, from the head of the screw 48 with which it normally engages, and then moving the 115 arm 50 to the left (toward the "parallel" indication), by means of the handle 52, and thus moving the bar 46 and the switches 5, 6, and 7 until their arms 8 have been moved to the left until they are brought against 120 their stop-pins 25 (see switch 6 in Fig. 1). If it is desired to simultaneously disconnect all the circuits from the repeater and then again connect all but a certain defective circuit or circuits with the repeater, for 125 reasons which are well understood by those skilled in this art, this can be quickly and conveniently done by disengaging the spring catch 58, by means of the knob 59, from the head of the screw 48 with which it normally engages, and then moving the arm 50 to the left, by means of the handle 52, until the switch arms 8 of the gang switches 5, 6 and 7 have been moved to the left until they 130 are brought against their stop-pins 25, then

withdraw the bolt 44 of such circuit or circuits as it is desired to leave disconnected and turn such bolts 44 so that their pins 56 will not be in line with the slots 54, and the bar 46 may then be returned to its normal position, and thereby return all switches to their normal position, which were not disconnected from the bar 46. When the defective circuit is repaired it may again be connected to the repeater by turning the bolt 44 of the gang switch of said circuit so that its pin 56 is in line with the slot 54 provided therefor, the bolt then being moved against the flat surface of the yoke 23 by the spring 55. The yoke 23 may now be moved from the left-hand position to the normal or repeater position and the bolt 44 will enter the notch 43. When the switch reaches its normal position, and the bar 46 being locked against movement, the movement of this switch will be arrested and it will be prevented from moving too far.

When the arm 50 has been moved to one of its abnormal positions, it may be rapidly returned to its normal position without fear of moving it past its normal position, as its motion will be arrested when it reaches its normal position by the engagement of either the spring catch 58 or 58' with a corresponding one of the screws 48.

If it is desired to operate one of the gang switches without moving any of the others, this can be done by first withdrawing the bolt 44 provided for actuating such gang switch, and then moving such switch by means of one of the knobs 24 provided thereon.

When the bar 46 is in its normal position, any gang switch which stands in abnormal position may be readily returned to its normal position without fear of moving it past its normal position, as its motion will be arrested when it reaches its normal position by the engagement of the bolt 44 with its corresponding slot 43.

We are aware that prior to our present invention, controlling systems have been used which have been made with a gang switch for simultaneously controlling the connection between each of a number of circuits and their respective signal responsive instruments, and switches for each of such circuits whereby any of such circuits may be taken from the control of the gang switch; and we are further aware, in constructing some of such gang switches provision was made whereby the individual switches comprising such gangs could be separately operated. We therefore do not claim such combinations broadly; but

What we claim is:

1. The combination with a series of switches of a detachable common actuating means, fixed abutments, oppositely arranged stop devices on said actuating means nor-

mally engaging said abutments, and arrangement of said stop devices to be capable of separate disengagement from said abutments.

2. The combination with a series of gang switches of a common actuating means, a detachable connection between said means and each of said gang switches, fixed abutments, oppositely arranged stop devices on said actuating means normally engaging said abutments, and arrangement of said stop devices to be capable of separate disengagement from said abutments.

3. The combination with a series of switches of a detachable common actuating means, fixed abutments, two oppositely arranged stop devices on said actuating means arranged to simultaneously engage said abutments and thereby lock the actuating means against movement in either direction, and arrangement of said stop devices to be capable of separate disengagement from said abutments.

4. A series of switches, each capable of occupying either of two extreme positions or one intermediate or normal position, a common actuating means for said switches, mechanism adapted to automatically lock said common actuating means in normal position when moved thereto from either extreme position, and detachable connecting means between said actuating means and each of said switches constructed and arranged to be adjusted to lock each of the switches in a certain position when the actuating means is locked in a certain position.

5. The combination with a series of switches of a detachable common actuating means, two latches controlling said actuating means, arrangement of one latch to tend normally to prevent movement of the actuating means in one direction, and arrangement of the other latch to tend normally to prevent movement of the actuating means in the other direction.

6. The combination with a series of switches of a detachable common actuating means, two latches arranged to hold said actuating means in intermediate position, arrangement of one of said latches whereby it may be disengaged to permit movement of the actuating means in one direction, and arrangement of the other of said latches whereby it may be disengaged to permit movement of the actuating means in the other direction.

7. A series of switches, each capable of occupying either of two extreme positions or one intermediate or normal position, a common actuating means for said switches, fixed abutments, oppositely arranged stop devices on said actuating means normally engaging said abutments, arrangement of said stop devices to be capable of separate disengagement from said abutments, and

detachable connecting means between said actuating means and each of said switches constructed and arranged to be adjusted to lock each of the switches in a certain position when the actuating means is locked in a certain position.

In witness whereof, we have hereunto sub-

scribed our names this 8th day of August, A. D., 1913.
